CLAIM

We claim the ornamental design for a four position power connector, as shown and described.

DESCRIPTION

FIG. 1 is a top, front and left perspective view of a four position power connector, showing our new design;

FIG. 2 is a bottom, rear and right perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.
